UNITED STATES PATENT OFFICE.

JAMES R. LITTLE, OF QUINCY, ILLINOIS, ASSIGNOR TO THE QUINCY METAL WHEEL COMPANY, OF SAME PLACE.

MANUFACTURE OF METAL WHEELS.

SPECIFICATION forming part of Letters Patent No. 361,952, dated April 26, 1887.

Application filed August 5, 1886. Serial No. 210,103. (No model.)

To all whom it may concern:

Be it known that I, JAMES R. LITTLE, of Quincy, in the county of Adams, and in the State of Illinois, have invented certain new and useful Improvements in the Manufacture of Metal Wheels; and I do hereby declare that the following is a full, clear, and exact description thereof, reference being had to the accompanying drawings, in which—

10 Figure 1 is a perspective view of a wheel constructed in accordance with my method and by my mechanism. Fig. 2 is an enlarged side elevation of a spoke and a central section of the hub, and of dies employed for securing said 15 spoke therein, said parts being shown in their relative positions before the action of said dies. Fig. 3 is a like view of the same after the spoke has been operated upon; and Figs. 4 and 5 are similar views of the compressing mechanism, 20 a spoke-end, and a portion of the rim, and show, respectively, the spoke before and after having been secured in place.

Letters of like name and kind refer to like parts in each of the figures.

25 In the use of metal wheels the greatest strain upon the spokes is where each enters the hub and rim, and when injury or breakage of a spoke occurs it is nearly always at one of such points, and usually results from a lack of 30 strength rather than a defect in the metal. 35 Another difficulty sometimes arises from the imperfect filling of a spoke-mortise, in consequence of which said spoke will work loose and soon render the wheel worthless for the purpose intended.

To remedy these difficulties is the design of my invention, which invention consists in the methods and mechanism employed, substantially as and for the purpose hereinafter specified.

40 In the carrying of my invention into practice I employ a metal hub, A, which has one row or two rows of radial equidistant mortises, a, each of which has a slightly-increasing diameter from its inner end outward, and is 45 adapted to receive a round metal spoke, B, that has such size as to enable it to be readily passed into the same.

To secure a spoke in position, the hub A is 50 placed upon a suitably-supported mandrel, C,

and a spoke, B, is inserted within one of the mortises a, with its lower end resting upon said mandrel, after which a pair of clamping-jaws, D, are caused to firmly grasp said spoke at a point above said hub, and then to move 55 downward, so as to compress it longitudinally between the point where it is grasped by said clamps and the mandrel.

The longitudinal compression of the spoke B produces such lateral expansion as to cause 60 it to closely fill the mortise a in the usual manner; but as such compression is mainly downward the tapering form of said mortise secures an important advantage, as it enables the entire 65 length of the latter to be filled, instead, as in the case of straight mortises, of filling the upper portion only.

In order that the spoke B may be stiffened and strengthened at and near the point where it enters the hub A, the clamping-jaws D are 70 arranged to grasp said spoke only at their upper ends, and from such point to their lower ends their confining-grooves d have a regularly-increasing diameter. Such construction causes said spoke to be compressed longitudinally for about twice the length which would be necessary for filling the mortise a, and gives to that portion immediately outside of said hub 75 an outwardly-tapering form. As by longitudinal compression alone the spoke is made 80 more strong and stiff, the taper described may be omitted, if desired.

The outer ends of the spokes B are secured within a rim, E, in the same manner as in the hub A, for which purpose the jaws D are employed, and in place of the mandrel C a plunger, F, is used, and is adapted to impinge upon the end of said spoke.

The method and mechanism employed renders practicable the production of a wheel 90 which will largely exceed in strength wheels having equal weight, but constructed, in the usual manner, with straight mortises and spokes.

It will be obvious that the principle of operation will be the same if the mandrel C and plunger F are arranged to move toward the clamping-jaws D, or said parts are adapted to be moved simultaneously toward each other, instead of having said mandrel and plunger 100

stationary and causing said clamping jaws alone to move.

Having thus described my invention, what I claim is—

- 5 1. As an improvement in the manufacture of metal wheels, the method of stiffening and strengthening the spokes, which consists in compressing each spoke longitudinally, so as to form upon or of the same at and immediately 10 outside of the point of its union with the hub an enlargement that has an outwardly-decreasing diameter, substantially as and for the purpose specified.
- 15 2. As an improvement in the manufacture of metal wheels, the method of stiffening and strengthening the spokes, which consists in compressing each spoke longitudinally, so as to form upon or of the same at and immediately 20 inside of the point of its union with the rim an enlargement that has an inwardly-decreasing diameter, substantially as and for the purpose 25 specified.
- 25 3. As an improvement in the manufacture of metal wheels, the method of combining the spokes with the hub, which consists, first, in forming within the hub a series of radial mortises that have each an outwardly-increasing 30 diameter, next in inserting within each mortise one end of a straight metal spoke, and finally compressing such spoke - end longitudinally until it closely fills the mortise, substantially as and for the purpose specified.
- 30 4. As an improvement in the manufacture

of metal wheels, the method of combining the spokes with the rim, which consists, first, in forming within the rim a series of radial mortises that have each an inwardly-increasing diameter, next in inserting within each mortise one end of a straight metal spoke, and finally compressing such spoke - end longitudinally until it closely fills the mortise, substantially as and for the purpose shown and described.

5. As an improvement in mechanism for manufacturing metal wheels, an organization in which are combined a mandrel which is adapted to form a bearing for the end of a spoke when the same is inserted within the mortise of a hub or rim, jaws that are provided within their inner faces with coinciding half-round tapering grooves, and are adapted to grasp a spoke within the smallest portion of said grooves at a point farthest from the mortise, means whereby said jaws may be pressed together upon the spoke, and means whereby said jaws and spoke-bearing may be relatively moved toward each other, substantially as and for the purpose specified.

In testimony that I claim the foregoing I have hereunto set my hand this 28th day of July, A. D. 1886.

JAMES R. LITTLE.
